(57) CLAIM

We claim the ornamental design for a pet dish and disposable liner, as shown.

DESCRIPTION

FIG. 1 is a perspective view of a pet dish and disposable liner according to our new design;

FIG. 2 is a top plan view thereof;

FIG. 3 is a right side view thereof;

FIG. 4 is a left side view thereof;

FIG. 5 is a bottom view thereof; and,

FIG. 6 is an exploded perspective view of the pet dish and disposable liner.
